DESIGN FOR A FRAME FOR LADIES' HANDBAGS

Wilford J. Kirst, Yonkers, N. Y.

Application August 8, 1941, Serial No. 102,746

Term of patent 3½ years

To all whom it may concern:

Be it known that I, Wilford J. Kirst, a citizen of the United States of America, residing in Yonkers, county of Westchester, and State of New York, have invented a new, original, and ornamental Design for a Frame for Ladies' Handbags, of which the following is a specification, reference being had to the accompanying drawing, forming part thereof.

The other side of the frame is substantially like the side shown.

I claim:

The ornamental design for a frame for ladies' handbags, as shown and described.

WILFORD J. KIRST.
